Holmes & French.
Forming Clouded Roving.

N° 8.948.

Patented May 18, 1852.

Fig. 1.

UNITED STATES PATENT OFFICE.

JONAS HOLMES AND EPHRAIM FRENCH, OF LEE, MASSACHUSETTS.

IMPROVEMENT IN CARDING BY WHICH VARIEGATED SLIVERS ARE PRODUCED.

Specification forming part of Letters Patent No. 8,948, dated May 18, 1852.

To all whom it may concern:

Be it known that we, JONAS HOLMES and EPHRAIM FRENCH, both of Lee, in the county of Berkshire and State of Massachusetts, have invented a new and useful Improvement in Carding-Machines for Making Variegated Roving or Slubbing; and we do hereby declare that the same is described and represented in the following specification and accompanying drawings.

The nature of our invention and improvement consists in traversing the doffers of carding-machines when the teeth upon the same are set in rings around the doffer-cylinder with spaces between them, and the different colors or materials are fed onto the card in strands, or a sheet composed longitudinally of different colors or materials, or so that the different colors or materials may be carded in the same spaces around the cylinders of the card upon which they are fed until they come to the doffer or doffers in which the teeth are set in rings around the same with vacant spaces between, so that as the doffer or doffers are traversed endwise the several colors or materials carded are caught in succession as the doffers are traversed over or across them, so as to make the roving variegated, it being composed alternately of the different colors or materials fed onto the card, with alternate spaces between the different colors or materials forming the connections between the said colors or materials, being composed of the said different colors or materials blended or mixed, so that the roving made by our invention and improvement may be variegated in color or material, or both, or mixed according to the feeding of the colors or materials onto the card, and the traversing of the doffer or doffers, and when two doffers are used the teeth upon one should be adjusted opposite the spaces upon the other, and vice versa, so that the material which is not caught from the card-cylinder by one may be caught by the other. The doffer or doffers may be made to traverse serpentine, zigzag, or alternately zigzag and serpentine, or with such curves, angles, or points as the operator may chose to adopt to produce the variety required in the roving; or the teeth upon the doffers may be set serpentine, zigzag, or both, or in such curves, angles, or points as may be desirable to pro-

duce the desired results, and when so set may be traversed endwise or not, as may be desirable or necessary to produce the variety desired in the roving produced. The wool or other materials carded may be taken from the doffers by the condensing-rollers in common use, or such other apparatus as will answer the purpose intended.

To enable others skilled in the art to make and use our invention, we will proceed to describe its construction and operation, referring to the accompanying drawings, in which the figure is a front view, showing such parts of the card as we deem necessary to describe our invention.

A represent sides of the card-frame made in the usual manner and connected together by girts.

B is the main cylinder covered with card-clothing in the usual manner.

C' represent doffers surrounded with rings of card-filletting, placed so that the fillet D on C comes opposite to the spaces D' upon C' between the fillets. The fillets or rings of teeth upon C may be made a little narrower than they are upon C', as C takes the wool from the main cylinder first, so that it may not get more than its share or proper portion. The bearings E E of the doffer-shafts are made as much longer than the boxes they turn in as the width of a fillet or space upon the doffer, or more, so that the doffers can be traversed by the cam F, fastened upon the shaft of C', which has a spiral groove in it, into which the point I of the stand H, fastened to the side A, projects. As the stand H is permanently fastened to the side, and the point I (represented by dotted lines) projects into the groove G, and as the doffer and cam F turn, the point I causes the doffer to traverse once across the width of the fillet during each quarter of a revolution of the doffer and back again the next quarter. The connecting-bar K, which is connected to the shafts of each of the doffers by the screws L L, so that the screws turn freely in said bar, causes the doffer C to move in concert with C', so that the fillets of teeth upon each doffer are opposite to the spaces between the teeth upon the other, the rotary motion of the doffers being made to correspond with each other by the wheels M M upon the ends of the doffer-shafts, both of which may be turned by the

long pinion N, which may be rotated by a pulley or gear fastened to it for that purpose. The card having been completed, as above described, the wool or other materials of different kinds or colors to be carded is fed onto the card, so as to cover the main cylinder alternately with red and black, as represented in the drawings. The doffers take the wool from the main cylinder as they are turned, and, traversed by the point I of the stand H, they catch red and black wool alternately as the fillets of teeth upon the doffers pass across the respective colors upon the main cylinder, so that when the fillet of teeth upon C is catching all black the teeth upon C' is catching all red, and as they are moved endwise the teeth upon C pass gradually from the space covered with black wool upon B to that covered with red, catching both black and red, as represented in the drawings, until it comes opposite to the red, when all the wool caught is red. At the same time the teeth upon C' had been passing from the space covered with red upon B to the space covered with black, and caught both red and black while making the change, until it catches all black. During this time the cam F has turned one-fourth way round, so that the point I is at the opposite apex of the cam, and as the doffers revolve the cam carries them back during the next fourth of a revolution to the point from whence they started, and if the card is kept in motion and supplied with wool, and the usual condensing-rollers or some proper apparatus to take off the wool from the doffers and convert it into roving is connected with it, it will make variegated roving, as described, which roving may be spun into the various kinds of yarn for such purposes as it may be wanted. We think it preferable to have the main cylinder so wide or the doffers so short that the rings

upon them will not traverse beyond the edge of the main cylinder, and as the yarn spun from the two outside rovings may be a little uneven we prefer to save it by itself until a sufficient quantity accumulates to use or weave it separately.

We contemplate that there are various devices that may be substituted for the cam to traverse the doffers, or that they may be made to traverse upon their shafts, or that the boxes in which the shafts turn may be traversed; also, that the main cylinder may be set in rings or strips around the cylinder, with narrow spaces between to make the colors more distinct, but the spaces should not be so wide as to reduce the size of the roving and make the yarn uneven.

What we claim as our invention and improvement, and desire to secure by Letters Patent, is—

Traversing the doffer or doffers of a card or setting the teeth upon them serpentine or zig-zag, or in such other curves, points, or angles as may suit the taste or fancy of the operator, also to traverse them when so set, if desirable, so as to take the wool or other materials from such parts of the main or other cylinder of the card and deliver it to the condensing-rollers or other apparatus, so as to make roving variegated either in colors or materials, or both, when said colors or materials are fed upon the card, substantially as described.

In testimony whereof we have hereunto signed our names before two subscribing witnesses.

JONAS HOLMES.
EPHRAIM FRENCH.
